UNITED STATES PATENT OFFICE

ALEXANDER H. HANDLAN, OF ST. LOUIS, MISSOURI.

LIGHT-SOURCE SUPPORT.

Application filed February 6, 1926. Serial No. 86,470.

This invention relates generally to light source supports, and particularly to an adjustable light source support which may be adjusted in a testing stand or testing lamp so that when said light source support is in use in a signal lamp, such as those used on railroads, the filament of the electric bulb which is associated with said light source support will be in the exact focus of the lens of said signal lamp.

At the present day a very great number of oil-burning signal lamps are employed on railroads. The introduction of the precision type of lamp bulb has made possible the use of electricity for lighting railway signal lamps, and because of the greater efficiency of the electric signal lamps those operators of railroad systems who have been using oil signal lamps are desirous of replacing them with electric signal lamps. In most cases, however, these operators have large stocks of oil-burning signal lamps on hand which, previous to this invention, would have to be discarded as useless in the event that said oil-burning lamps were replaced by electric signal lamps, and this loss has prevented to a great extent the universal adoption of the more efficient signaling means.

In view of the foregoing I have evolved the light source support disclosed in the present application, which may be aptly described as an adapter, due to the fact that the use of said light source support converts an oil-burning signal lamp into an electric signal lamp.

To obtain satisfactory results in the use of a precision type electric bulb in a signal lamp the filament of the bulb must be located with precision in the focal center of the lens and an important feature of my invention resides in the fact that my improved supporting device includes means whereby the bulb may be adjusted to bring the filament thereof into the proper position with respect to the lens of the lamp. The purpose of the present invention, therefore, is to produce a light source support which is capable of being introduced into the housing of a signal lamp of the oil-burning type to permit the use of electric lamp bulbs therein and which is so constructed and arranged that said light source support may be adjusted either in a testing stand or test-

ing lamp previous to being placed in a signal lamp in service or in the service lamp itself to properly position the filament of the bulb with respect to the lens of the lamp.

Another object of my invention is to produce a light source supporting unit which includes as an element thereof a reflector. In this form of the invention adjusting means are provided whereby the filament of the bulb may be located in the exact focus of the reflector.

Fig. I is a rear elevation of my improved light source support.

Fig. II is a fragmentary view, partly in side elevation and partly in vertical section, showing my improved light source support arranged in a sheet metal signal lamp.

Fig. III is a fragmentary vertical section on line III—III of Fig. II.

Fig. IV is a plan view of my improved light source support.

Fig. V is a side elevation of the support shown in Fig. IV.

Fig. VI is a cross section on line VI—VI of Fig. V.

Fig. VII is a fragmentary sectional detail showing one of the adjusting screws of my improved device.

Fig. VIII is a fragmentary view, partly in vertical section and partly in elevation, showing a second form of my invention arranged within a cast iron signal lamp.

Fig. IX is a cross section on line IX—IX of Fig. VIII.

In Fig. II of the drawings, A designates a sheet metal signal lamp which comprises a side wall B, a bottom wall C, a vertically slidable door D, and a lens E. The lens E is fixed in place in the lens opening of the lamp in any suitable manner, and the construction of the lamp is the usual and ordinary construction of lamps of the type illustrated.

Located within the lantern A is my improved light source support, which comprises a base member 1 which, as is shown in Figs. III and IV, has considerable width. Extended upwardly from the base member 1 adjacent to the forward edge thereof is a pair of extensions 2 having each a threaded opening 3 formed therethrough. The extensions 2 are preferably, though not necessarily, formed integral with the base member 1, and said extensions are aligned with each

other in a direction transversely of said base member 1.

4 designates a bracket comprising a base plate 5 and a supplemental supporting plate 6, said plates overlapping each other as shown clearly in Figs. II and V and being rigidly fixed together by means of a pair of screws or other suitable fastening devices 7. In producing my improved support I prefer 10 to form the support 6 of fiber or other material of a non-conducting nature and to make the base plate 5 of a suitable metal. 8 designates a sleeve which extends upwardly from the support 6 at the rear end portion 16 thereof, said sleeve having an integral laterally extended flange 9 through which a fastening device, preferably a screw 10, passes. The screw 10 is screwed into a threaded opening in the fibrous support 6, whereby 20 said sleeve is rigidly fixed to said plate. 11 designates a bolt which passes upwardly through an aperture in the supporting plate 6, the head portion 11' of said bolt being in contact with the bottom face of said support 25 6 and the shank portion of said bolt passing through an aperture in the flange 9. 12 designates a pair of nuts arranged one above the other on the shank portion of the bolt 11, the lowermost nut of said nuts 12 30 being in firm contact with the top face of the flange 9 whereby the bolt 11 functions as an additional fastening device for securing the sleeve 8 to the plate 6. 13 designates a nut which is arranged above the nuts 12 on 35 the shank portion of the bolt 11, the last mentioned nut being adapted to be screwed downwardly on the bolt 11 to grip an electric conductor *b* between said nut 13 and the uppermost nut 12, whereby, in addition to 40 aiding the fastening device 10 in securing the sleeve 8 to the plate 6, said bolt 11 functions as a binding post which electrically connects the conductor *b* to the flange 9. The sleeve 8 is split, as shown in Fig. IV, 45 and extended into said sleeve is an electric socket 14 adapted to receive an electric lamp bulb 15. 16 designates a screw extended through ears 17 formed on the sleeve 8 at the slit therein whereby said ears 17 may be 50 drawn together to cause the sleeve 8 to frictionally grip the electric socket 14.

18 designates a conducting member which is secured to the plate 6 by means of a bolt 19, said bolt being extended through an aperture in the contact member 18 and through 55 an aperture in the supporting plate 6. The head portion 19' of the bolt 19 is in contact with the lower face of the contact member 18, and a pair of nuts 20 are screwed on the threaded shank portion of said bolt in such 60 manner that the lowermost nut 20 is in firm contact with the top face of the sleeve supporting plate 6. 21 designates a nut screwed on the shank portion of the bolt 19, said 65 nut 21 being adapted to be screwed into firm

contact with an electric conductor *a* which is interposed between said nuts 21 and the uppermost nut 20 whereby said electric conductor is electrically connected to said bolt 19 and consequently to the contact member 18. A portion of the contact member 18 passes through an aperture in the supporting plate 6 and contacts with a pin 22 forming a part of the electrical socket 14. Also the contact element 23 of the electric lamp bulb 70 is in contact with said pin 22, as shown by dotted lines in Fig. I. It is plain, in view of the arrangement just described, that electrical energy passing through the conductor *a* will pass through the bolt 19 into and 75 through the contact member 18, said energy passing from said contact member through the pin 22 in the socket 14 to the filament of the electric bulb. The electrical circuit through which electrical energy is caused to 80 pass to the electric bulb 15 includes the conductor *b* which is grounded to the sleeve 8 through the instrumentality of the bolt 11 and nuts 12 and 13.

By referring now to Fig. VI it will be 85 noted that the base 5 is provided with a pair of elongated apertures 25 which are spaced apart from each other and are aligned with each other in a direction longitudinal of said plate. When my improved device 90 is in an assembled condition the base 5 is arranged with respect to the base member 1 so that the elongated openings 25 are in vertical alignment with the threaded openings 3 in the extensions 2 formed on said base 95 member 1. Extended through the elongated openings 25 and screwed into the threaded openings 3 in the extensions 2 is a pair of screws 26, there being suitable washers interposed between the head portions of said 100 screws and the adjacent portions of the top face of the base 5. Extended through threaded openings 27 formed through the base 5 is a pair of screws 28. The screws 28 are spaced apart from each other and are 105 aligned with each other in a direction longitudinal of the base 5, and the lower end of each of said screws bears against the top face of the base member 1, as shown in Figs. II and V.

110 In explaining the use of my improved light source support it will be assumed first that the light source supports are being adjusted for use in sheet metal signal lamps of the type illustrated in Fig. II. In other 115 words, it will be considered that sheet metal signal lamps provided with means for burning oil are being converted into electric signal lamps, the oil-burning apparatus and the oil reservoirs, etc., formerly associated with said signal lamps having been removed therefrom, leaving only the guide members 29 shown in Fig. III.

120 Each of the light source supports which are to be placed in sheet metal signal lamps 130

may be adjusted previous to being placed in a lamp so that the filament of the associated electric bulb will be in the exact focus of the lens of the lamp, and this adjustment is effected in the following manner:

Either at the factory where the light source supports are made or at the shop of the railroad which is to use the supports a testing stand, or testing lamp, is maintained. 10 This testing stand, or testing lamp, is an exact counterpart of the sheet metal signal lamps in so far as dimensions are concerned, and said sheet metal lamps are of course all standard. It is plain, therefore, that if a 15 light source support having an electric bulb associated therewith is adjusted in the testing stand, or testing lamp, so that the filament of said bulb is in the exact focus of the lens of said testing stand, or testing 20 lamp, said light source support may be removed from the testing stand, or testing lamp and be arranged in any sheet metal signal lamp of the same size and type as the testing stand or testing lamp, and the 25 filament of the bulb will be in exactly the proper position with respect to the lens of the last mentioned lamp to obtain the greatest efficiency.

To adjust the light source support an 30 electric lamp bulb is arranged in the socket 14 and the support is then arranged in a testing stand, or testing lamp. The screws 26 and 28 are then manipulated to move the bracket 4 so as to bring the filament of 35 the electric lamp bulb supported by said bracket to the proper position. For instance, assume that the filament of the electric bulb were slightly below the exact center of the lens. In this event the screws 40 26 would be rotated in a direction to cause the heads of said screws to be moved upwardly from the top face of the base 5, after which the screws 28 would be rotated in a direction to cause the entire bracket 4 and 45 the bulb 15 to be moved upwardly until the filament of the bulb is in the proper position. Also, if it be assumed that the filament of the bulb is too far away from or 50 too close to the lens to be in the proper focus thereof, the screws 28 would be manipulated; or if the filament of the bulb be offset from its proper position in a direction laterally with respect to the signal lamp the bracket 4 would be tipped by causing the 55 head of one or the other of the screws 26 to be lower than the associated screw 26. When either of the screws 28 is being manipulated to adjust the bracket 4, said bracket together with the bulb supported thereby pivots 60 about the lower end of the associated screw 28, and when either of the screws 26 is manipulated to adjust the bulb laterally of the signal lantern said bracket and bulb pivot about the lower ends of both of the screws 65 28. When an adjustment has been made

and the filament of the bulb brought to the desired position the screws 26 are screwed downwardly so as to cause the head portions thereof to bear firmly against the top face of the base 5, whereby accidental movement of said plate, which would destroy the adjustment thereof, is prevented. 70

It is apparent in view of the foregoing that an electric lamp bulb supported by my improved light source support is capable of 75 universal movement whereby the filament of said electric bulb may be located in the exact focus of the lens of the testing stand, or testing lamp.

In the use of my improved light source 80 support I prefer to employ the so-called precision electric bulbs. These bulbs are so made that their filaments are universally positioned in exactly the proper relation to the geometric centers of the bulbs, and therefore if the light source is adjusted so that the filament of one precision bulb is in proper relation with respect to the lens of the signal lamp, said precision bulb may then be removed from the lamp and other 85 precision bulbs located therein, and because the filaments of all of the precision bulbs are properly positioned within the bulbs all of said filaments will be in the exact 90 focus of the lens of the lamp. It is plain, 95 therefore, that the light source support is adjusted with a precision lamp bulb associated therewith, after which said support is arranged in a signal lamp, and thereafter whenever the electric bulb burns out or is to be replaced for any other reason, a new precision bulb may be arranged within the signal lamp with its filament in the proper focus of the lens of the lamp without again 100 adjusting the light source support. It is apparent, however, that ordinary commercial 105 bulbs may be used, and in this event the light source support will be adjusted either in a testing stand or testing lamp or in the service lamp in which the bulb is to be used, 110 each time a new bulb is installed.

In Fig. VIII I illustrate a form of my invention which will be used in signal lamps having cast iron housings. It has been found in the case of cast iron signal lamps 115 that the bottom walls of the housings frequently warp or otherwise become misshapen, and therefore when my improved light source support is used within cast iron signal lamps I form a plurality, preferably four, threaded apertures 30 through the base member 1' of the light source support. Extended through each of the threaded openings is a screw 31, said screws having each a pointed lower end portion 120 which contacts with the bottom wall of the signal lamp. When my device is provided with the screws 31 and the bottom wall of the lamp is not perfectly level, said screws 125 may be manipulated to bring the base mem- 130

ber 1' to exactly the proper level position. To provide for free movement of the base member 1' relative to the bottom wall of the lamp, I provide said base member with 5 a bottom face 1^a having tapered corner portions and thereby eliminate any chance that the corners of the base member will strike the bottom wall of the lamp and interfere with the movement of said base member.

10 In Fig. VIII also I illustrate the form of my invention which includes a reflector 32 forming a part of the light source supporting unit. The form of the invention which includes a reflector is intended for use with 15 a lamp provided with a roundel E' instead of a lens. The reflector may be of any suitable type and is preferably supported by a frame 33 which is secured directly to the base member 1' in any convenient manner, 20 so that the light source support and the reflector comprise a complete unit. Reflectors of the type used with my light source support are merely molded and consequently the focal centers of said reflectors are not 25 uniformly located and for this reason I arrange the bracket 4' of the form of the invention shown in Fig. VIII so that it is capable of being adjusted by manipulating the screws 26' and 28'. In this manner the 30 filament of the bulb 15' associated with the light supporting unit may be positioned in the exact focus of the reflector forming a part of said light supporting unit.

The means for adjusting the bracket 4' is 35 an exact counterpart of the means for adjusting the bracket 4 shown in Figs. II and V and for that reason need not be described in detail.

In connection with the use of the form of 40 the invention shown in Fig. VIII, precision bulbs may be used in which event the bracket 4' need be adjusted only once after which other precision bulbs may be associated with the light source support from 45 time to time without readjusting said bracket. However, when ordinary commercial bulbs are employed it will be necessary to readjust the bracket 4' each time a new bulb is introduced.

50 I claim:

1. A device for focusing a lamp relatively to a reflector, comprising, in combination, a support having apertures therein, adjusting members extending through the apertures, 55 a fibrous supporting plate secured to and offset from the support, a lamp supporting

sleeve carried by the fibrous supporting plate, and binder posts mounted on the fibrous supporting plate for connecting the lamp supporting sleeve with electric terminals, the support being operable by means of the adjusting members to impart tilting adjustment in all directions to the lamp supporting sleeve. 60

2. A device for use in focusing a lamp 65 relatively to a reflector comprising, in combination, a base, a lamp support disposed above the base for adjustment relatively thereto, a rigid member extending upwardly from the base through a passageway formed in the support, the member being provided with a head for limiting the upward movement of the support relatively to the base, an annular contraction formed intermediate 70 between the ends of the passageway in the support, the diameter of the contraction being approximately the same as the diameter of the rigid member extending upwardly from the base, whereby the lamp support is free to tilt relatively to the rigid member and the base, but is held against sidewise movement relatively thereto, and means for imparting tilting adjustment to the support. 75

3. A device for use in focusing a lamp 80 relatively to a reflector comprising, in combination, a base, a lamp support disposed above the base for adjustment relatively thereto, a rigid member extending upwardly from the base through a passageway formed 85 in the support, the member being provided with a head for limiting the upward movement of the support relatively to the base, an annular contraction formed intermediate 90 between the ends of the passageway in the support, the diameter of the contraction being approximately the same as the diameter of the rigid member extending upwardly from the base, whereby the lamp support is free to tilt relatively to the rigid member 95 and the base, but is held against sidewise movement relatively thereto, and means for imparting tilting adjustment to the support, said means comprising a plurality of members spaced from the rigid member, 100 adapted to abut against the base and to have screw threaded engagement with the lamp support. 105

In testimony that I claim the foregoing I hereunto affix my signature. 110

ALEXANDER H. HANDLAN.
